[57] CLAIM

The ornamental design for a golf club weight, substantially as shown and described.

DESCRIPTION

FIG. 1 is a top perspective view of a golf club weight showing my new design.

FIG. 2 is a front elevational view of the weight of FIG. 1. The weight is shown in this FIG. 2 and in FIGS. 3 through 6 as it appears when clamped to the shaft.

FIG. 3 is a rear elevational view of the weight of FIG. 1.

FIG. 4 is a bottom plan view of the weight of FIG. 1. FIG. 5 is a side view of the weight as viewed from the right side of FIG. 1.

FIG. 6 is a side view of the weight as viewed from the left side of FIG. 1.

FIG. 7 is a perspective view thereof with the straps in open position.

FIG. 8 is a top perspective view of a second embodiment of the golf club weight.

FIG. 9 is a front elevational view of the weight of FIG. 8. The weight is shown in this FIG. 9 and in FIGS. 10 through 13 as it appears when clamped to the shaft.

FIG. 10 is a rear elevational view of the weight of FIG. 8.

FIG. 11 is a bottom plan view of the weight of FIG. 8. FIG. 12 is a side view of the weight as viewed from the right side of FIG. 8.

FIG. 13 is a side view of the weight as viewed from the left side of FIG. 8.

FIG. 14 is a perspective view of the weight of FIG. 8 with the straps in open position.

The broken line showing of a golf club shaft and head in FIGS. 1 and 8 is to show environment only.
